Specification for Design.

Patented May 9, 1916.

Application filed August 11, 1914. Serial No. 856,158.

To all whom it may concern:

Be it known that I, GEORGE V. ANDERSON, of Wilmington, in the county of New Castle and State of Delaware, have invented certain new and useful Improvements in Leather-Working Machines, whereof the following is a specification, reference being had to the accompanying drawings.

My invention relates to a leather working machine which is particularly designed for applying to a skin or hide a liquid coating or seasoning which is usually applied to the grain side of the skin.

According to my invention the skin which is to be treated is carried around the under side of a rotating drum, being held in place thereon by a series of cords. As the drum rotates, carrying the skin, a succession of cylindrical brushes apply a liquid to the skin or brush liquid thus applied into the skin, as will be hereinafter more particularly described.

In the accompanying drawings, Figure I, is a front elevation of a machine embodying my invention. Fig. II, is a rear elevation of the same. Figs. III and IV, are the two end elevations of the machine. Fig. V, is a section along the line V, V, of Fig. I. Figs. VI to IX inclusive, are detailed views of the scraper mechanism. Fig. X, is a detail showing the method of adjusting certain of the brush rollers with respect to the supporting drum for the skins. Fig. XI, is a detail of the strainer in the liquid receptacle. Fig. XII, is a detail cross section through the seasoning liquid supply pan, showing the adjustable overflow pipe therefor; and Fig. XIII, is a modified form of slack take up for the retainer cords which hold the skin in contact with the supporting drum during their passage through the machine.

Referring to Fig. V, the drum 1, which is preferably a large metal cylinder, mounted on spider frames 2, rotates in the direction of the arrow. A series of endless cords or wires 3, pass around the grooved roller 4, and thence against the lower and rear surface of the drum, moving in the same direction, and at the same rate as the drum, until they reach the grooved roller 5, around which they pass and thence descend and return to the grooved roller 4, after passing around the guide rollers 6 and 7. The

grooves of the rollers 4, and 5, maintain these cords at properly spaced intervals, assisted by a comb 8. A tension roller 9, rests with its weight against the series of cords and maintains pressure to equalize the tension of the cords against the drum, and keep them under a constant and yielding tension as they pass around under it. This tension roller 9, is mounted on arms 10, 10, swinging upon the shaft 11.

The application roller 13, which is preferably a cylindrical brush, rotates in the direction of the arrow. The lower part of this roller is submerged within the liquid contained in the pan 14, while the upper part of the roller comes in contact with the surface of the skin passing around the drum and applies the liquid to its surface, notwithstanding the intervening cords, which are relatively small and interfere very slightly with the even application of the liquid. The brush roller 15, rotating as indicated by the arrow, serves to thoroughly disseminate the liquid over the surface of the skin, and to throw off the surplus liquid. The brush roller 16, rotating in the same direction further accomplishes the same purpose.

The brush roller 17, with which the skin comes next in contact, rotates in the opposite direction from the brush rollers 16 and 15. It is mounted upon the shaft 11, and carries a roller 18, with an oscillating cam groove, within which is received the roller 19, by means of which the brush roller 17, is given an oscillatory motion as it rotates. This oscillatory motion enables the brush to disseminate the liquid beneath the portions of the skin underlying the cords, which are by the oscillation of the brush rolled slightly to one side or the other. The movement of this brush in the opposite direction from that of the brush 16, serves the further useful function of applying the liquid to all parts of a horizontal fold if the same shall have formed in the skin at any point, and upon which the previous brushes rotating in the opposite direction may have applied the liquid only to one side.

The brush roller 20, rotates as indicated by the arrow and completes the thorough application of the liquid to all parts of the skin operating upon it after it has left the cords so that all parts of the surface of the

skin are necessarily reached by the brush. This brush roller 20, while rotating, is in a similar manner to brush roller 17, given an oscillatory motion by means of the cam roller 21, carried by its shaft, and having a cam groove in contact with a stationary roller, as seen in Fig. II.

It is an important characteristic of my machine that the liquid is applied to the under side of the skin from which it is free to drip off without running over the surface of the drum, and without being splattered over the machine. Any surplus liquid is brushed off by the rollers 15, and 16, and drips into a splash pan 22, near the bottom of the machine. This splash pan drains through an opening 23, into a reservoir 25, from which the liquid is again elevated as needed through the pipe 26, by means of a pump 27, from which the feed pipe 28, returns the liquid to the pan 14. Within the reservoir 25, is situated a cylinder 29, the lower part of which is perforated, while the upper part, corresponding to the normal level of the liquid, is not perforated. (See Fig. XI). The pipe 26, draws from within this cylinder, which is useful in order to prevent any of the foam which tends to form on the surface of the liquid in the reservoir from being drawn into the pump. In order to prevent overflowing of the pan 14, an adjustable threaded stand pipe 30, protected by two lock nuts, is provided, as shown in Fig. XII. This overflow pipe 30, also discharges into the drip pan 22.

The driving mechanism for the drum and the several brushes already described comprises a shaft 32, upon which are mounted the usual tight and loose pulleys 33 and 34, respectively. This shaft is journaled in a standard 35, and also in the side frames 36, 36, of the machine, and carries a pinion 37, which, through a spur gear 38, drives the stub shaft 39.

45 The drum 1, is mounted on a shaft 40, which is journaled in bearings 41, 41, formed at the top of the side frames 36, 36, of the machine. At one end shaft 40, is provided with a spur gear 42, which is driven from a pinion 43, on the stub shaft 39.

55 The cords or wires 3, are positively driven from the grooved rollers 4, and 5, which are connected by a sprocket chain 45, as best seen in Fig. IV. The shaft 46, upon which roller 5, is mounted, carries at its other end (Fig. III) a sprocket 47, which is driven by means of a chain 48, from a sprocket 49, also mounted upon the stub shaft 39. By 60 this arrangement the cords 3, are constantly and positively driven, the contact with the grooves of rollers 4, and 5, being at all times maintained by the tension upon the cords through the instrumentality of the 65 weighted roller 9. The guide rollers 6, and

7, for the cords merely act as idlers, and are supported for rotation by means of bolts 50. See Fig. I. These bolts are adjustably secured to brackets carried by the side frames of the machine and are provided with tapered ends which engage the trunnions 51, of the rolls 6 and 7. By this means the resistance to driving offered by these rolls is reduced to a minimum.

Application brush 13, is driven by means of a chain 52 (Fig. IV) from a sprocket 53, mounted on shaft 54, which carries the grooved cord driving roller 4. This shaft also drives by means of a chain 55, the pump 27, already described. Brush 16, is driven directly from the pulley shaft 32, by means of a chain 57, (see Fig. III) and the shaft upon which this brush is mounted, in turn drives the brush 15, by means of a chain 58, see Fig. IV. Brush 20, is driven by means of a chain 59, from a sprocket 60, also carried by the stub shaft 39, as best seen in Fig. III. At the opposite end of the machine (Fig. IV) the shaft 61, upon which brush 20, is mounted, carries a sprocket 62, which through a chain 63, drives the brush roller 17. By this system of driving the several brushes are rotated in such a manner as to thoroughly apply and evenly distribute the seasoning liquid upon the skins.

Special arrangements are provided for regulating the tension with which the various brushes press against the skin as it passes around the drum.

Feeding brush 13, is supported by arms 65, 65, loosely mounted adjacent the side frame 36, on the shaft 54, which carries the cord driving roller 4. These arms are adjustably suspended from the frames 36, 36, by means of rods 66, which are threaded and secured to brackets 67. By the manipulation of nuts 68, on rods 66, the brush 13, may be readily adjusted with respect to the drum 1. Brush 15, is similarly suspended in arms 69, from shaft 32, and may be likewise adjusted with respect to the drum 1, by means of a threaded rod 70. Brushes 16, 17 and 20, are mounted in adjustable bearings, each comprehensively indicated at 71. These bearings are all similar in construction and for convenience one of the bearings for roll 20, has been chosen for illustration in detail in Fig. X. It will, of course, be understood that this description will hold good for all of them. In this figure the bearing 71, is slidably mounted upon the standard 36, by means of bolts 72, which pass through slots 73, in the frame. The bearing is supplemented by a boss 75, which is internally threaded and engaged by a screw thread formed on the inner end of a stub shaft 76, which carries a bevel pinion 77. By rotation of the shaft 76, the bearing 71, may be readily adjusted so that the brush 20, may be moved toward or away

110
115
120
125
130

from the drum 1, as circumstances may require. The bearings 71, 71, for the roll 20, are adapted to be simultaneously adjusted by means of a hand wheel 78, which is mounted on a shaft 79 (see Fig. II), having bevel pinions 80, which mesh with the bevel pinions 77, already described.

The seasoning liquid employed in connection with this machine, is of an adhesive nature and for this reason, it is imperative that the brushes be removed from contact with the drum during any idle periods of the machine. This may be readily accomplished by the mechanism just described. 15 When the machine is, however, again put into operation, it is likewise imperative that the brushes resume their original adjustment with respect to the drum, 1. To this end, I have provided adjustable stop screws 81, 20 for the bearings 71. These screws are mounted in lugs 82, projecting from the side frames 36. The brushes may by this means be retracted from the drum 1, and again returned to their active positions, 25 without destroying the original adjustment. On the main figures of the drawings these stop screws 81, have been illustrated only in connection with the brush 20, it being, of course, understood that each of the brushes 30 of the group just described is, in actual practice, supplemented with the screws.

In front of the machine is mounted a table 83, by which the skin is guided as it is passed down between the drum and the 25 cords. There is also provided a transverse scraper 85. This scraper is illustrated in detail in Figs. VI to IX inclusive. It is preferably formed of hard rubber and supported by a plate 86, which extends practically the full width of the machine and is 30 adjustably mounted (as will be explained later) upon inclined extensions 87, projecting from the side frames 36. The scraper is provided with a metallic backing strip 88, and these are together adjustably held between the plate 86, and a guiding plate 89, secured to the spacing ridge 90, formed on plate 86. The adjustment of scraper 85, is 35 accomplished by means of a series of set screws 91, which are threaded into the ridge 90, and engage the backing strip 88, for the scraper. This adjustment is essential for wear compensation and for maintaining close contact of the scraper with respect to 40 the surface of the drum, so that the portion of the drum presented at the feeding point is absolutely clean. This is very important in that the value of the finished product is 45 greatly decreased when stained upon the flesh side.

In order to prevent the scraper from sticking to the drum during the idle periods of the machine, for the same reason as already pointed out in connection with the 50 several brushes, the plate 86, is so mounted

upon its supports 87, as to be capable of being retracted with respect to the drum 1. This is accomplished by means of eccentrics 92, one at each side of the machine. These eccentrics are mounted for rotation 55 in the extensions 87, and engage squared apertures 93, (Fig. IX) on the ends of the plate 86, and are actuated through the instrumentality of hand levers 95. Plate 86, is guided in its lateral motion by means of 60 stud bolts 96, which are secured in the extension 87, and pass through slots 97, in the said plate. It will be readily seen that a half rotation of the eccentrics 92, will suffice to retract the scraper from contact 65 with the drum during the idle periods of the machine. Here again the construction of the parts just described is such as to permit the retraction and return of the scraper without destroying the original adjustment 70 of the scraper by means of screws 91. The liquid scraped from the drum collects in the gutter formed by the angle of inclination of the scraper with respect to the drum, and drips off the ends into 75 the splash pan 22. Conduits may be provided to direct the liquid from the ends of this gutter but no attempt has been made to illustrate these, in order to avoid complicating the drawings. 95

In Fig. XIII, I have illustrated a modified means for maintaining the proper tension on the cords 3. In this modification each cord is provided with a grooved tension roller 100. This roller is mounted in an 100 arm 101, pivotally attached to a lug 102, secured to an angle iron 103, adapted to extend the full width of the machine and to be attached to the side frames 36. The arm 101, is slightly overbalanced at the roller 105 end, so that gravity will at all times hold the roller in engagement with its cord and thereby compensate for the slack. By use of this modification the slack of each cord may be taken up individually since as before stated, there is one of these rollers for each cord. 110

In operation the skins are fed by hand over the table 83, and carried by the continuous movement of the drum and gears 115 down and around the drum into successive contact with the brushes, the grain surface of the skin being always exposed to such brushes. The cords hold the skin evenly and flatly against the drum, preventing the 120 wrinkling or kinking thereof, and preventing the edges of the skin from turning over and the shanks of the skin from kicking up. This device combined with the application of the seasoning liquid to the under side of the skin prevents the unintentional and objectionable application of liquid to the 125 flesh side of the skin, as occurs in other varieties of machinery intended for the same purpose. As the skin passes around the 130

4
drum the seasoning liquid is applied to it by the brush 13, any surplus liquid dripping off into the pan, or being brushed off successively by the brushes 15 and 16, which further assist the working of the liquid into the skin. The amount of liquid taken up by the brush is carefully regulated by adjusting the overflow pipe in relation to the pan. As the skin progresses it meets the oscillating brush 17, by which the cords are sufficiently vibrated to work the liquid against the underlying parts of the skin and any horizontal kinks turned over the same, the same function being still further performed by the roller 20, after passing which, the skin is removed by the operator from the drum, as it is passing over the top thereof, and a new skin applied.

Having thus described my invention, I claim:

1. In a leather working machine the combination of the rotary drum; a series of endless cords or wires rotating with the drum and in contact with a portion of its periphery; and brush rollers for applying seasoning liquid to the surfaces of skins as they pass around that portion of the periphery of the drum against which they are held flat by the pressure of said cords or wires.

2. In a leather working machine the combination of the rotary drum; a series of endless cords or wires rotating with the drum and in contact with the lower part of its periphery; and means for applying treatment to the surfaces of skins as they pass around the lower part of the periphery of the drum.

3. In a leather seasoning machine the combination of a rotary drum; means for holding skins in contact with the drum as said skins pass around the under surface thereof; means including a feed pan for applying liquid to the surface of the skins as they pass under the drum; a splash pan beneath the machine by which surplus liquid is collected; and means for returning surplus liquid to the feed pan.

4. In a leather seasoning machine the combination of a rotary drum; means for holding skins in contact with the drum as said skins pass around the under surface thereof; means, including a feed pan, for applying liquid to the surface of the skins as they pass under the drum; a splash pan by which surplus liquid is collected; a reservoir beneath the splash pan into which the said splash pan drains and a pump and feed pipe by which the contents of the reservoir are returned to the feed pan.

5. In a leather seasoning machine a rotary brush for applying liquid to leather mounted to rotate below the surface of the skin to be treated and with its upper periphery in contact with the skin; a pan below the brush containing seasoning liquid, within which

the lower part of the brush is submerged; and means for controlling and regulating the supply of liquid to the pan.

6. In a leather seasoning machine, a rotary brush for applying liquid to leather, mounted to rotate below the surface of the skin to be treated and with its upper periphery in contact with the skin; a pan below the brush containing seasoning liquid, within which the lower part of the brush is submerged; and means for maintaining the liquid at a fixed level in the pan.

7. In a leather working machine the combination of a rotary drum; endless cords or wires rotating with the drum in contact with a portion of its periphery, whereby skins under treatment are held against the surface of the drum; and means for maintaining said cords under yielding tension.

8. In a leather seasoning machine, the combination of a rotary drum; endless cords or wires rotating with the drum in contact with a portion of its periphery, whereby skins under treatment are held against the surface of the drum; a roller mounted on swinging arms, whereby it rests its weight against said cords, thereby maintaining a uniform tension throughout said cords.

9. In a leather working machine, the combination of a rotary drum; endless cords or wires rotating with the drum in contact with a portion of its periphery, whereby skins under treatment are held against the surface of the drum; and means individual to each cord for maintaining it at predetermined tension.

10. In a leather seasoning machine, the combination of a rotary drum; endless cords or wires rotating with the drum in contact with a portion of its periphery, whereby skins under treatment are held against the surface of the drum; grooved rollers individual to each cord mounted on arms pivoted on a single bar, and so mounted that the weight of each roller bears against its respective cord, thereby maintaining a uniform tension at all times.

11. In a leather working machine the combination of a rotary drum; a series of endless cords or wires; two rollers with grooves corresponding to each cord around which said cords are carried; said grooved rollers being mounted in such relation to the drum as to hold said cords in contact with a portion of the periphery of the drum.

12. In a leather working machine the combination of a rotary drum; a series of endless cords or wires; two rollers with grooves corresponding to each cord around which said cords are carried; said grooved rollers being mounted in such relation to the drum as to hold a definite portion of each cord as it passes from one grooved roller to the other against the corresponding portion of the periphery of the drum.

13. In a leather working machine the combination of a rotary drum; a series of endless cords or wires; two rollers with grooves corresponding to each cord around which said cords are carried; said grooved rollers being mounted in such relation to the drum as to hold a definite portion of each cord as it passes from one grooved roller to the other against the corresponding portion of the periphery of the drum; and means for guiding the cords away from contact with the drum as they pass back from one grooved roller to the other.
14. In a leather working machine the combination of a rotary drum; a series of endless cords or wires; two rollers with grooves corresponding to each cord around which said cords are carried; said grooved rollers being mounted in such relation to the drum as not to touch the periphery of the drum or permit the cords while on the rollers to touch the drum, but in such a position as to hold a definite portion of each cord as it passes from one grooved roller to the other against the corresponding portion of the periphery of the drum.
15. In a leather working machine the combination of a rotary drum; a series of endless cords or wires; two rollers with grooves corresponding to each cord around which said cords are carried; said grooved rollers being mounted in such relation to the drum as to hold a definite portion of each cord as it passes from one grooved roller to the other against the corresponding portion of the periphery of the drum; and means for guiding the cords away from contact with the drum as they pass back from one grooved roller to the other, said means including a comb whereby said cords are maintained at properly spaced intervals.
16. A leather seasoning machine comprising a rotary drum; means for holding a skin in contact with the periphery of the drum, with exposure of one surface thereof; a rotary brush for applying liquid to said surface, the periphery of said brush rotating constantly in the direction in which said surface moves; and another brush rotating constantly in the opposite direction for removing the surplus of the liquid thus applied.
17. A leather seasoning machine comprising a rotary drum; means for holding a skin in contact with the periphery of the drum, with exposure of one surface thereof; a rotary brush for applying liquid to said surface, and successive brushes rotating in opposite directions for removing the surplus liquid.
18. In a leather seasoning machine the combination of a rotary drum; means for holding a skin in contact with the periphery of the drum during part of its rotation, with exposure of one surface of the skin; and means for applying a liquid thereto consisting of a cylindrical brush, one side of which is submerged in the liquid to be applied and the other side in contact with the skin, and which rotates so that when the drum and the brush are in contact, they constantly move in the same direction.
19. In a leather working machine a rotary drum; spaced cords whereby skins are held against the under surface of the drum with exposure of all of one surface of each skin except the parts covered by the cords; and means for slightly varying the lateral position of the cords as the drum rotates.
20. In a leather seasoning machine the combination of a rotary drum; a series of endless cords or wires rotating in contact with a portion of the periphery of the drum; means for applying liquid to the exposed portions of skins carried between the drum and the cords, and a brush which simultaneously rotates and oscillates to effect sufficient vibration of the cords to distribute the liquid beneath the surfaces, otherwise protected by them.
21. In a leather seasoning machine the combination of a rotary drum; a series of endless cords or wires rotating in contact with a portion of the periphery of the drum; means for applying liquid to the exposed portions of skins carried between the drum and the cords; and a rotary brush for spreading said liquid with its surface in contact with the skins carried by that portion of the periphery of the drum which is not in contact with the cords.
22. In a leather seasoning machine, the combination of a rotary drum; spaced cords in contact with the under portion only of the periphery of the drum, whereby skins are held against the drum as they pass beneath it with exposure of all of one surface except the parts of it covered by the cords; means for applying seasoning liquid to the skins as they pass between the drum and the cords; and means for distributing said liquid situated so as to operate upon the skins still lying on the periphery of the drum but after they have passed away from contact with the cords.
23. In a leather working machine the combination of a rotary drum; means for holding skins in contact with the periphery of said drum as it rotates; a rotary brush which is in contact with the surface of the skins carried by the drum; means for adjusting said brush and setting it at a definite pressure position against the surface of the drum; and means whereby said brush may be removed from contact with the drum and thereafter restored to said contact with maintenance of the same definite pressure without disturbing the original adjustment.
24. In a leather working machine, the combination of a rotary drum; means for

holding a skin in contact with the periphery of the drum during a part of its rotation; a scraper operating against the surface of the drum after the skins leave it; 5 means for adjusting said scraper and setting it at a definite pressure position against the surface of the drum; and means whereby said scraper may be removed from contact with the drum and thereafter restored to 10 said contact with the maintenance of the

same definite pressure without disturbing the original adjustment.

In testimony whereof I have hereunto signed my name at Philadelphia, Pennsylvania, this seventh day of August, 1914.

GEORGE V. ANDERSON.
